UNITED STATES PATENT OFFICE.

DAVID S. WILLIAMS, OF PHILADELPHIA, PENNSYLVANIA.

DESIGN FOR A LAMP-BODY.

SPECIFICATION forming part of Design No. 32,141, dated January 23, 1900.

Application filed December 23, 1899. Serial No. 741,474. Term of patent 7 years.

To all whom it may concern:

Be it known that I, DAVID S. WILLIAMS, a citizen of the United States of America, residing at No. 903 Walnut street, in the city and county of Philadelphia, State of Pennsylvania, have invented a new and original Design for a Lamp-Body, of which the following is a specification.

My invention relates to a new and original design for the lamp-body or mixing-chamber of a petroleum incandescent lamp, and is more particularly adapted to that class of lamps producing a light of high candle-power with an incandescent mantle by the use of kerosene-oil vapor under considerable pressure.

Referring to the accompanying drawings, forming part of this specification, Figure 1 illustrates a perspective view of a lamp-body or mixing-chamber, showing my new design; and Fig. 2 represents a plan view of the same.

As illustrated in the drawings, the leading or material feature of my design consists of a vertically-disposed tube or chamber A, provided at the top with an inverted-U-shaped connection A', which terminates in a conical or bell-shaped portion A². The bottom of the tube or chamber A is provided with diverging curved branches A³ and A⁴, upon the respective ends of which are arranged cylindrical burner-heads B B'.

Having described my invention, what I claim, and desire to secure by Letters Patent, is—

The design for a lamp-body substantially as herein shown and described.

Signed by me at Philadelphia, Pennsylvania, this 21st day of December, 1899.

DAVID S. WILLIAMS.
